UNITED STATES PATENT OFFICE.

HARTWELL B. SHIPPEE, OF KILLINGLY, CONNECTICUT.

SCREEN FOR WINDOWS AND SCREEN DOORS.

Application filed January 31, 1922. Serial No. 533,053.

To all whom it may concern:

Be it known that I, HARTWELL B. SHIPPEE, a citizen of the United States, residing at Killingly, in the county of Windham and State of Connecticut, have invented certain new and useful Improvements in Screens for Windows and Screen Doors, of which the following is a specification, reference being had therein to the accompanying drawings.

This invention relates to screens for windows, door screens, piazza screens, interior screens, and in screens for any purpose where wire, cloth or other flexible material is to be fastened to a frame, and the object of the invention is the provision of simple and efficient means for holding the wire cloth or wire mesh securely upon the frame.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a perspective view of a window screen constructed in accordance with my invention, showing partly a portion of the molding in section.

Figure 2 is a sectional view, taken on line 2—2, Fig. 1, and looking in the direction of the arrows.

Figure 3 is a fragmentary, perspective view of the frame.

Figure 4 is a fragmentary, perspective view of another embodiment of the frame, which type or style of frame may be used if so desired instead of the slight modification as shown in Fig. 3.

Referring to the drawings by numerals, 1 designates a frame in which is formed a channel or groove 2 which extends entirely around the frame. The inner edge 3 is lower than the outer edge 4 (Fig. 3); on the edge 3, the wire cloth or mesh 5 rests; the thickness of the wire mesh is equivalent to the difference in the height of the outer edge 4 above the inner edge 3. In other words, I have produced a window-screen or door-screen frame having a groove extending entirely around the same with the inner edge of the frame contiguous to the groove lower than the outer edge of the frame at the groove for the purpose hereinafter described.

In the embodiment shown in Fig. 4, the

structure of the channel or groove 2 is the same as shown in Fig. 3, except in this embodiment I eliminated the formation of the inner edge 3, by making (in Fig. 4) the edge 3^a on the same horizontal plane with the edge 4; the operator or the constructor can utilize either method, as he prefers, under the scope of the appended claims.

The outer wall 6, of groove 2, is straight, whereas, the inner wall 7, of the groove, is rounded or bevelled decidedly to permit the wire mesh to be drawn or readily depressed into the groove 2 by the rounded tongue 8 of the molding 9.

The assembling of the frame, wire mesh and molding is accomplished by first laying the wire cloth or wire mesh on the frame, then fastening two contiguous pieces of the molding upon the wire mesh, as shown in Fig. 1, then to tighten the wire mesh upon the frame, I place the third piece of molding over a portion of the groove 2, with the wire mesh resting under the molding, then I force the tongue 8 of the molding into the groove causing a slight drawing action on the wire mesh down into the groove over the inner edge 3, over the rounded wall 7, and then I use ordinary nails or tacks to permanently fasten the molding upon the frame; in the same manner I apply or fasten the remaining or fourth piece of molding upon the frame.

It is to be noted, upon referring to Figs. 2 and 3, that the wire mesh 5 rests against the inner edge 3 of the frame and is equivalent to the difference in the height of the inner edge 3 and the outer edge 4, so that the faces 10 of the molding 9 will rest even against the frame and wire mesh, resulting in a neat appearance.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In a device of the character described, the combination of a frame having a continuous groove extending entirely there-around in one face thereof, said groove being comparatively deep and narrow and

having an inner and outer wall, the outer wall being straight and parallel to the outer edge of said frame, the inner wall extending at an acute angle to the inner edge of said frame and having beveled corners, a wire mesh fitting upon said frame and extending into said groove, a moulding having a comparatively broad head entirely covering said groove and having a comparatively long rounded tongue fitting within said groove for holding said mesh in position without danger of injury thereto, as and for the purposes set forth.

2. In a device of the character described, the combination of a frame having a continuous groove extending entirely therearound in one face thereof, said groove being comparatively deep and narrow and having an inner and outer wall, the outer wall being straight and parallel to the outer edge of said frame, the inner wall extend-

ing at an acute angle to the inner edge of said frame and having beveled corners, and being of less height than the outer wall, a wire mesh fitting upon said frame and extending into said groove, a moulding having a comparatively broad head entirely covering said groove and having a comparatively long rounded tongue fitting within said groove for holding said mesh in position without danger of injury thereto, and securing means for holding said moulding upon said frame, whereby the outer wall of the groove will tip said moulding over slightly onto the inner wall, thereby binding the moulding upon the mesh at this point and also causing the tongue to wedge more firmly within said groove, as and for the purposes set forth.

In testimony whereof I hereunto affix my signature.

HARTWELL B. SHIPPEE.
